DIAMOND WITH SPECIALLY FACETED PAVILION

James Huisman and Harry Huisman, Westchester County,
N.Y. (both of 630 5th Ave., New York, N.Y.)
Filed Jan. 10, 1964, Ser. No. 337,065
6 Claims. (Cl. 63—32)

This invention relates to a new and improved faceted diamond construction and particularly, a brilliant diamond construction.

The term "brilliant" as hereinabove and hereinafter used is a term of art, designating a "brilliant" cut as illustrated for example, in Goldstein Patent No. 2,340,659 issued on February 1, 1944 and such design patents as D. 49,305 issued to Samuel Heller on July 4, 1916 and D. 40,693 issued to Ernest G. H. Schenck on May 17, 1910.

The present invention relates principally to the lower portion of the stone, commonly known as its pavilion, that is, the portion below its outer peripheral edge, known in the trade as the girdle. The upper portion of the stone, known as the crown and table, may be of conventional design. The girdle itself may either be plain or faceted and parallel or non-parallel with respect to the vertical or longitudinal axis of the stone. In short, both the girdle and the upper portion of the stone may be of any conventional design and their only bearing upon the present invention resides in the fact that their brilliance and life are enhanced by the present improvement in the design and structure of the pavilion.

In conventional brilliant designs there are twenty-four facets in the pavilion, cut and polished at an angle of approximately 41 degrees with respect to the plane of the girdle. It will be understood that the vertical or longitudinal axis of the stone is perpendicular to the girdle plane and consequently, these twenty-four facets are disposed at an angle of approximately 49 degrees with respect to the vertical. As stated and shown in the Goldstein patent above mentioned, the pavilion normally has "conventional twenty-four facets."

The principal object of this invention is the provision of a new and improved diamond cut in which the pavilion is formed of seventy-two facets.

More specifically, and this will be discussed in greater detail in the description to follow, the seventy-two facets herein provided consist of eight kite facets of one shape, sixteen kite facets of another shape, sixteen star facets which are actually of diamond shape, and thirty-two facets of triangular shape. Kite shaped and triangular shaped facets are commonly used in the pavilion of a brilliant as illustrated in the Goldstein patent above mentioned. However, in the present construction two differently shaped kite designs are employed as well as a star or diamond shaped design. This is not conventional and certainly not in the numbers of facets herein provided.

Among the advantages of the present construction are the following:

(1) A new ornamental appearance is provided by reason of the fact that a greater number of facets (seventy-two instead of the conventional twenty-four) are used and at least some of these facets are cut at different angles from those commonly used. A more flowing design is thereby achieved.

(2) Enhanced life or brilliance results from the present construction and particularly from the combination of the greatly increased number of facets in the pavilion and the different angles at which a great many of them are cut. The total number of facets in the present stone, assuming a conventional design in the crown and table, is 106; the total for a conventional stone is 58.

2

(3) The present construction provides for increased resistance to chipping. Fewer facets necessarily are joined by sharper or more acute corners or ridges; a larger number of facets necessarily are joined by corners or ridges which are more obtuse. Obviously, the relatively acute corners are more prone to chipping than those which are relatively obtuse.

The invention is illustrated in the accompanying drawing in which:

10 FIGURE 1 is a bottom view of a diamond shaped in accordance with the present invention.

15 FIGURE 2 is a side view thereof looking in the direction of arrows 2—2 of FIGURE 1.

15 FIGURE 3 is a top plane view of said diamond looking in the direction of arrows 3—3 of FIGURE 2.

15 FIGURE 4 is a schematic view showing the angles of the facets in the present invention.

20 Referring now to the details of the present invention as illustrated in the drawing, it will be observed that a diamond 10, of pavilion cut or design, is provided with a conventional crown 12 surmounted by a conventional table 14. Encircling the lower edge of the crown is a conventional girdle 16. The drawing shows the girdle to be unfaceted but this is purely illustrative and it will be understood that a faceted girdle, such as is shown in the above mentioned Goldstein patent, may also be used in conjunction with the present invention. The particular design or cut of the crown and table, as illustrated in FIGURES 2 and 3, is intended to be purely conventional and it will be appreciated that various conventional designs for these portions of the stone may be employed in connection with the present invention.

25 Turning now to the pavilion 18 of stone 10 and particularly to FIGURES 1, 2 and 4 of the drawing, it will be observed that the said pavilion comprises the following cut and polished facets: Eight kite-shaped facets 20 meeting at a culet 22, sixteen kite-shaped facets 24, sixteen star or diamond shaped facets 26 and thirty-two triangular facets 28. It will be observed that kite-shaped facets 20 differ both in shape and orientation from kite-shaped facets 24. In kite-shaped facets 20 the wider end, terminating at a relatively more obtuse angle, points downwardly while in kite-shaped facets 24 the narrower, more acute end, points downwardly. In short, the orientation of kite-shaped facets 24 is reversed a full 180 degrees from the orientation of kite-shaped facets 20. It will be noted that there are twice as many kite-shaped facets 24 as there are kite-shaped facets 20, there being two facets 24 between each pair of facets 20.

30 FIGURE 1 clearly shows that the shorter sides of kite-shaped facets 20, which define the more obtuse angle and form the lower end thereof, adjoin each other. The longer sides of said kite-shaped facets 20 which meet at a more acute angle and form the upper ends of said kite-shaped facets 20, adjoin the longer sides of kite-shaped facets 24 which meet at a more acute angle and form the lower ends of said facets 24.

35 Adjoining the shorter sides of kite-shaped facets 24, which sides meet at a more obtuse angle and form the upper ends of said kite-shaped facets are the diamond or star-shaped facets 26. Adjoining the opposite sides of said diamond or star-shaped facets 26 are the triangular facets 28. The opposite sides, actually the bases of said triangular facets 28, adjoin girdle 16. The angles at which facets 20, 24, 26 and 28 are formed with respect to the horizontal, that is, the plane of the girdle when the longitudinal axis of the stone is vertical, are as follows:

40 Kite-shaped facets 20—41 degrees

45 Kite-shaped facets 24—45 to 47 degrees

Diamond-shaped facets 26—53 to 54 degrees
Triangular facets 28—58 to 60 degrees

In the foregoing list of angles it is understood that the horizontal, meaning the plane of the girdle, is situated at zero degrees and the longitudinal or vertical axis is situated at 90 degrees. The culet 22 would also be oriented at zero degrees, that is, in a horizontal plane parallel to the plane of the girdle.

The foregoing is illustrative of a preferred form of this invention. It will of course, be understood that minor modifications thereof, such as slight variations in the angles above listed, would be encompassed within the broad principles of the invention. Furthermore, although the invention has above been described in connection with a diamond, it will be appreciated that it may equally as well be applied to other precious stones.

What is claimed is:

1. A brilliant-cut precious stone having a faceted crown and a faceted pavilion with a girdle interposed between the crown and pavilion, said pavilion having seventy-two facets formed thereon, wherein the seventy-two facets consist of the following: thirty-two triangular facets adjoining the girdle; sixteen diamond-shaped facets adjoining said thirty-two triangular facets; sixteen kite-shaped facets adjoining said diamond-shaped facets; and eight additional kite-shaped facets adjoining said first mentioned kite-shaped facets.

2. A brilliant-cut precious stone in accordance with claim 1, wherein the triangular facets are situated at an angle of approximately 58 degrees to 60 degrees with respect to the plane of the girdle, the longitudinal axis of the stone being perpendicular to said plane.

3. A brilliant-cut precious stone in accordance with claim 1, wherein the diamond-shaped facets are situated at an angle of approximately 53 degrees to 54 degrees with respect to the plane of the girdle, the longitudinal axis of the stone being perpendicular to said plane.

4. A brilliant-cut precious stone in accordance with claim 1, wherein the first mentioned kite-shaped facets are situated at an angle of approximately 45 degrees to

47 degrees with respect to the plane of the girdle, the longitudinal axis of the stone being perpendicular to said plane.

5. A brilliant-cut precious stone in accordance with claim 1, wherein the additional kite-shaped facets are situated at an angle of approximately 41 degrees with respect to the plane of the girdle, the longitudinal axis of the stone being perpendicular to said plane.

10 6. A brilliant-cut precious stone having a faceted crown and a faceted pavilion with a girdle interposed between the crown and pavilion, said pavilion having seventy-two facets formed thereon, wherein the pavilion consists of thirty-two triangular facets adjoining the girdle, and situated at an angle of approximately 58 degrees to 60 degrees with respect to the plane of the girdle, the longitudinal axis of said stone being perpendicular to said plane; sixteen diamond-shaped facets adjoining said triangular facets and being situated at an angle of approximately 53 degrees to 54 degrees with respect to the plane of the girdle; sixteen kite-shaped facets adjoining said diamond-shaped facets and situated at an angle of approximately 45 degrees to 47 degrees with respect to said plane of the girdle; and eight additional kite-shaped facets adjoining said first mentioned kite-shaped facets and situated at an angle of approximately 41 degrees with respect to said plane of the girdle, said additional kite-shaped facets meeting at a culet which is positioned on the longitudinal axis of the stone in a plane parallel to the plane of the girdle.
